CLAIM

The ornamental design for an ostomy attachment, as shown and described.

DESCRIPTION

FIG. 1 is a front perspective view of an ostomy attachment; FIG. 2 is a top plan view of the ostomy attachment of FIG. 1;

FIG. 3 is a bottom plan view of the ostomy attachment of FIG. 1;

FIG. 4 is a left side plan view of the ostomy attachment of FIG. 1;

FIG. 5 is right side plan view of the ostomy attachment of FIG. 1;

FIG. 6 is a front view of the ostomy attachment of FIG. 1; and,

FIG. 7 is a back view of the ostomy attachment of FIG. 1. Any portions of the ostomy attachment shown in broken lines depict environmental subject matter only and form no part of the claimed design.
